US0D1042447S

(12) **United States Design Patent** (10) Patent No.: **US D1,042,447 S**
 Suda et al. (45) Date of Patent: ** Sep. 17, 2024

(54) **ELECTRONIC MODULE HOUSING**

- (71) Applicant: **Aptiv Technologies AG**, Schaffhausen (CH)
- (72) Inventors: **Timothy Alan Suda**, Avon, IN (US); **Tobias Richter-Brockmann**, Düsseldorf (DE)
- (73) Assignee: **Aptiv Technologies AG**, Schaffhausen (CH)
- (**) Term: **15 Years**
- (21) Appl. No.: **29/797,215**
- (22) Filed: **Jun. 29, 2021**

(57) CLAIM

We claim the ornamental design for an electronic module housing, as shown and described.

DESCRIPTION

FIG. 1 is a left side perspective view of an electronic module housing showing the design; and,

FIG. 2 is a top plan view of the electronic module housing of FIG. 1.

The broken lines shown represent unclaimed subject matter and form no part of the claimed design.

The relatively light and thin shade lines show contour and not surface decoration.

The portion of the article that is not illustrated in the Figures
is not claimed.
